(57) **CLAIM**

The ornamental design for a sample analyzer, as shown and described.

DESCRIPTION

FIG. 1 is a top, front, and right-side perspective view of a sample analyzer according to one embodiment of the present invention;

FIG. 2 is a top, rear, and left-side perspective view of the sample analyzer shown in FIG. 1;

FIG. 3 is a front elevational view of the sample analyzer shown in FIG. 1;

FIG. 4 is a rear elevational view of the sample analyzer shown in FIG. 1;

FIG. 5 is a left-side elevational view of the sample analyzer shown in FIG. 1;

FIG. 6 is a right-side elevational view of the sample analyzer shown in FIG. 1;

FIG. 7 is a top plan view of the sample analyzer shown in FIG. 1; and,

FIG. 8 is a bottom plan view of the sample analyzer shown in FIG. 1.

The surface shading and surface ornamentation, if any, illustrated in the drawings is provided merely to highlight the contour of the design; it is not intended to be illustrative of texture or gloss.
